(57) **CLAIM**

The ornamental design for a vibrator unit, as shown and described.

DESCRIPTION

FIG. 1 is a front perspective view of a vibrator unit showing my new design.

FIG. 2 is a rear perspective view of the vibrator unit, opposite that of FIG. 1.

FIG. 3 is a right side view of the vibrator unit.

FIG. 4 is a left side view of the vibrator unit.

FIG. 5 is a front view of the vibrator unit.

FIG. 6 is a rear view of the vibrator unit.

FIG. 7 is a top plan view of the vibrator unit; and,

FIG. 8 is a bottom plan view of the vibrator unit.

The broken lines in the drawings depict unclaimed environmental subject matter.
